Primary Examiner — Ian Simmons*Assistant Examiner* — Tyenne A. Fulton-Crosson(74) Attorney, Agent, or Firm — Olive Law Group, PLLC(57) CLAIM

The ornamental design for a chair, as shown and described.

DESCRIPTION

FIG. 1 is a perspective view of a chair;

FIG. 2 is a front view thereof;

FIG. 3 is a rear view thereof;

FIG. 4 is a left side view thereof;

FIG. 5 is a right side view thereof; and,

FIG. 6 is a top view thereof.

The broken lines shown in the drawings are for the purpose of illustrating portions of the article and form no part of the claimed design.

1 Claim, 6 Drawing Sheets(56)
